CLAIM

The ornamental design for a battery pack, as shown and described.

DESCRIPTION

A portion of the disclosure of this patent document contains material which is subject to copyright protection. The copyright owner has no objection to the facsimile reproduction by anyone of the patent document or the patent disclosure as it appears in the United States Patent and Trademark Office patent file or records but otherwise reserves all copyright rights whatsoever.

FIG. 1 is a front view of a battery pack;

FIG. 2 is a rear view of a battery pack;

FIG. 3 is a top view of a battery pack;

FIG. 4 is a bottom view of a battery pack;

FIG. 5 is a left view of a battery pack;

FIG. 6 is a right view of a battery pack;

FIG. 7 is a detailed view of section 7 of FIG. 1;

FIG. 8 is an isometric view of a battery pack;

FIG. 9 is a detailed view of section 9 of FIG. 8; and,

FIG. 10 is a detailed view of section 10 of FIG. 8.

(Continued)

The broken lines depict environment and portions of the article that form no part of the claimed design.
